UNITED STATES PATENT OFFICE.

FRANK L. DECKER, OF KIMBLE, PENNSYLVANIA.

BUILDING FORM.

Application filed June 21, 1924. Serial No. 721,542.

My present invention has reference to a building construction in which stone or concrete slabs are employed, the said slabs being arranged in courses and having their edges 5 provided with confronting grooves, while means of a novel nature is employed for holding the inner and outer slabs in spaced relation, for inserting a concrete between the joints thereof and for producing a building having a dead air space between the walls thereof.

A still further object is to simplify and improve the building construction upon which I have received U. S. Letters Patent 15 No. 1,451,144, granted April 10, 1923, in a manner whereby substantially half of the material employed in the patented construction is utilized with the improvement.

To the attainment of the foregoing and 20 other objects which will present themselves as the nature of the invention is better understood, reference is to be had to the drawings which accompany and which form part of this application.

25 In the drawings:—

Figure 1 is a side elevation of a building in the course of construction in accordance with this invention.

Figure 2 is a horizontal sectional view on 30 the line 2—2 of Figure 1.

Figure 3 is a plan view of the corner of the building.

Figure 4 is an enlarged sectional view approximately on the line 4—4 of Figure 1.

35 Figure 5 is a similar sectional view approximately on the line 5—5 of Figure 4.

Figure 6 is an enlarged fragmentary sectional view on the line 6—6 of Figure 1.

Figure 7 is a perspective view of the 40 outer corner plate.

Figure 8 is a similar view of the horizontal corner plate.

Figure 9 is a similar view of the inner corner plate.

45 Figure 10 is a similar view of the inner wall plate.

Figure 11 is a similar view of one of the horizontal plates which connect the vertical wall plates.

50 Figure 12 is a similar view of the longitudinal spacer plate.

Figure 13 is a similar view of the removable and adjustable extension for the spacer plate.

55 In carrying out my present invention, I employ parts substantially similar to those

disclosed in my Patent No. 1,451,144 and therefore will not set forth in detail the construction of such parts more than is necessary to clearly set forth my present improvement.

As shown in the drawings the building construction includes inner and outer superimposed courses of slabs which have their edges longitudinally grooved and if necessary their ends may be likewise grooved.

The wall construction is laid on a concrete foundation 1 and embedded in the upper face of the said foundation there are metal strips or plates having inturned ends to receive the longitudinal grooves of the lower course of inner and outer slabs 2.

This construction has not been illustrated, as the same has been clearly set forth in my referred to patent. The upturned ends of the plates receive therebetween the inner vertical wall plates 3.

The wall plates 3, as well as the inner and outer corner plates 4 and 5 are of a construction set forth in my patent, it being here deemed only necessary to say that the same have their bottoms flanged, notched and slotted and their upper edges formed with projecting tongues and with slots.

The substantially U-shaped wall plates 3 are of a length equaling the width of the slabs 2, and as disclosed by the drawings are disposed alternately at the opposite sides of the wall.

The tongues 6 and 7 on the top of the wall of the alternately arranged vertical wall plates 3 are designed to be passed through angularly arranged slots 8 and 9—9 on the horizontal tie plates 11, while the flanged base 12 of the vertical wall plates 3 are designed to have their slots 13 received between right angularly arranged upstanding flanges 14 on the said horizontal tie plates 11.

Each of the tie plates 11 has its body inclined inwardly from its ends to its center and its inclined edges are flanged, as at 14.

100 The straight outer edges of the said plates are also flanged, as at 15, in the direction of the flanges 9. The body of the plates adjacent the said flanged ends 15 are slotted at spaced intervals and the metal bounded by the slits is rounded upwardly to provide flanges 16 disposed opposite the flanges 15, and shorter angle flanges 17 at the sides of the flanges 16.

105 Each of the plates 11, at the side thereof provided with the slots 8 and 9 is formed with an opening 18, the purpose of which will presently be apparent. The

110

flanges 15 and 16 are received in the grooves of the confronting courses of slabs 2, the flanges 17 spacing the said courses, so that mortar poured through the openings 18 at 5 the alternate sides of the horizontal layer of plates 11 will seep into the horizontal joints of the slabs. The base 12 of the vertical plates 3 are really in the nature of flanges, and therefore will not retard the downward 10 flow of mortar. To provide for this, as well as to provide a spacing means for the substantially U-shaped plates 11 I produce angle plates, illustrated in Figure 12. The horizontal flange 19 of the spacer plate is centrally slotted both vertically and longitudinally and the metal bounded by the slits is bent angularly in the same direction to provide spaced arms 20. These arms have in-turned ends 21. The inturned portions or 15 arms 20 are designed to straddle the substantially U-shaped vertical wall plates 3, the flanges thereof engaging the edges of the flanged sides of the said plates. The horizontal element of the spacer plate is indicated by the numeral 22, and has its edges bent to form ways 23 for a plate 24 illustrated in Figure 13. The plate 24 is slid through its ways until the same contacts with the inner faces of the wall structure. 20 The ends of the vertical element of the wall plate are slotted vertically to provide upper tongues 25 and lower tongues 26, the upper tongues 25 designed to be received through slots or notches 27 at the juncture of the 25 flanges with the body of the vertical plates at the ends thereof as well as in central notches 28 in the plates 11. The horizontal corner plates are substantially similar to those set forth in my patent and engage the 30 outer and inner vertical plates 4 and 5 in substantially the same manner. The horizontal corner plates 29, however, are preferably formed from a single sheet of metal and have their edges bent to form oppositely extending flanges on their outer corners and 35

spacer flanges 30 between the lower spaced flanges to be received between and to space the joints at the corner of the construction so that mortar will flow into said joints.

In my present construction it will be noted that mortar is alternately poured from both of the inner sides of the building construction in the course of the erection thereof, and that substantially one-half of the metal and mortar used in my patented construction is 55 employed in the improvement. The improvement, it may be stated, is primarily directed to small buildings and bungalows.

While it is believed that the foregoing description, when taken in connection with the drawings will fully set forth the details of my construction and the advantages thereof, it is to be understood that I am not to be restricted to the precise structural details disclosed, but am entitled to all such changes 60 65 therefrom as fairly fall within the scope of what I claim.

Having described the invention, I claim:—

A hollow wall construction comprising two spaced courses of slabs which are arranged in 70 staggered relationship in the same course and also with relation to the other course, said slabs having grooves extending across their two horizontal surfaces, tie plates having flanges received in said horizontal 75 grooves, horizontally arranged spacer plates of a length equal to the length of a slab supported by said tie plates, said spacer plates consisting of horizontal elements, the ends of which receive the tie plates, and vertical 80 elements in right angular relationship, said vertical elements being slotted centrally and having spaced arms with in-turned ends which straddle U-shaped vertical wall plates of the height of a slab and a filling of mortar 85 in the voids formed by said spacer plates and said wall plates.

In testimony whereof I affix my signature.

FRANK L. DECKER.
